MINE LAYING SUBMARINE

Amato Capponi, Taranto, Italy

Application April 1, 1935, Serial No. 14,163
In Italy April 5, 1934

13 Claims. (Cl. 114—17)

There are two types of mine discharging mechanisms in use today. The first employs horizontal tubes of a diameter about equal to that of the mine. The disadvantages of this type are known, and are as follows:—Only a relatively few mines may be carried in a given space for the apparatus; no adequate provision is made for the examination and care of the mines in the tubes; the passage of the mine along its tube and its discharge therefrom is effected by power transmission gearing which acts on the rack of the mine, and, as the rack does not always keep in line, defective displacement occurs; the fall of the mine cannot always be governed and, as the mine must always pass from the horizontal to the vertical position, it must describe a parabola trajectory which is more or less arbitrary and therefore prejudicial to accurate manipulation; and each mine tube must have two water-tight doors and a complicated system of tubing for the flooding, exhausting and compensating operations.

The second type of mine discharging mechanism uses discharge tubes that are vertically disposed, or almost vertical, and are placed laterally or centrally of the ship in free communication with the sea, and having a diameter about equal to that of the mine. This type of discharge tube requires the employment of a large number of tubes so that a sufficient number of mines may be kept ready, and therefore a considerable amount of space and work room is required, and operating is difficult; no provision is made for examination and care of the mines which are kept immersed in sea-water and consequently are subject to galvanic action, incrustation, oxidation, and so on, with the consequent likelihood of the mines becoming injured so as to be inoperative.

Therefore it is an object of the invention to overcome the objectionable features above referred to, and to provide an arrangement which permits of the formation, especially in submarines, of one or more mine chambers, and to arrange them in relation to the divisional water-tight partitions of the compartments and utilize part of the space occupied by said partitions.

The invention is illustrated in the preferred form of execution, given solely as a non-limitative example, in the annexed drawings, in which:

Fig. 1 represents, somewhat diagrammatically in longitudinal section, a type of installation for submarines, with three chambers which are flush with the compartments occupied by: the room

containing the instruments of control, the workroom and so on.

Fig. 2 is a plan view thereof.

Fig. 3 is an enlarged view in longitudinal section of a mine chamber illustrating the disposition of mines contained in it. 5

Fig. 4 is a plan view of the structure shown in Fig. 3, parts being omitted.

Fig. 5 is a transverse section, on an enlarged scale, of a portion of a vessel fitted with the 10 present invention and showing the position and contents of the mine-carrier cage at the bottom of the discharging chamber.

Fig. 6 shows in section, on an enlarged scale, the disposition of the pivoted brackets of the 15 mines fixed to the cage and the device for the rotation of the cage.

Fig. 7 shows in section, on an enlarged scale, the disposition of the pivoted brackets of mine 20 dischargers rotating and oscillating on their own axes.

Fig. 8 illustrates, in a front view partially in section, the disposition of the blocking device of the hand wheel control of the oscillatory pivoted brackets, to avoid any error of the mine dis- 25 charger.

In reference to the drawings in which the same reference number distinguished the same parts, a systematization is shown with three mine chambers for a submarine. The mine chambers are 30 of the type for 15 mines in 3 layers. Each mine chamber is formed of a watertight metal cylinder 1 (Fig. 3) firmly connected to the hull 2 itself.

In the inside of the cylinder, and concentrically 35 with it, is arranged a metal cage mine-carrier 3 which rotates on its own axis and is supported at the base by two rims of conical roller bearings 4 (Figs. 5 and 6).

The vertical centralization of the cage, both 40 during the rotation and in a state of repose is secured by the application of the rollers 5 (Figs. 3 and 5) arranged at the two extremities of the cage.

At the base of the mine-carrier cage is fixed a 45 gear wheel 6 (Figs. 3, 5 and 6) which, receiving the rotation movement from the gearing 7 (Figs. 3 and 6) causes the cage to rotate on its own axis. The gearing 7 is worked in its turn by a special motor, and is provided with a handle operating emergency apparatus.

The placing of the mines in the cage is done in the following way:

First, the watertight door 8 (Figs. 1 and 3) situated at the top of the mine chamber is opened; 55

Second, the cage is made to rotate until the opening of the door 8 coincides with one of the mine beds 9 (Fig. 4);

Third, the first mine is then placed inside so that it rests on the lower pivoted brackets 23 (Figs. 3, 5 and 7) which are fixed to the cage;

Fourth, then the second mine is put in, so that it rests on the central pivoted brackets 23 (Figs. 3 and 7);

10 Fifth, then the third mine is put in so that it rests on the upper pivoted brackets 23;

Sixth, when the first three mines have been introduced, the cage is made to rotate again so that the second mine bed is in correspondence 15 with the door 8, and the operation of putting in the three mines is repeated as at letters c, d, e;

Seventh, the operation of rotating the cage and putting in the three mines is repeated until all 20 the mine beds are full;

20 Eighth, when the operation is complete, the door 8 is closed.

The mines can always be inspected, either with the ship afloat or immersed. This inspection is made in the following way:

25 Opening the watertight door 11 (Fig. 4), access is got to the recess 12, which, through the watertight door 13, one passes to the landing 14 and using the stairway 15, reaches the three central platforms constructed of metal gratings 16, 30 from which it is easy to inspect all the mines.

Each mine, bearing with its own weight on the extremity of the two pivoted brackets 23 (Figs. 3 and 6), tends to make them rotate on the shaft 19 and thence to free itself in the descent, but this 35 rotation of the pivoted brackets is prevented, since the other extremities of the said pivoted brackets, namely, those furnished with the sliding rollers 20, engages with on the rings 21 and 22 which are fixed in the cylinder 1.

40 The two rings 21 and 22 are interrupted for a space in correspondence with the discharge door 17 and their sliding plane in this space is taken by two movable planes 24, each of which is controlled by a nonreversible couple 25 formed by a worm and a worm wheel. This couple is worked 45 contemporaneously from the inside of the ship by the hand wheel control 26 on the spot and eventually, by motor and at a distance.

The operation of the pivoted brackets for mines 50 is worked by the transmissions 27, 28, 29 (Fig. 8) one for each couple of pivoted brackets worked by the respective hand wheel control 26.

To avoid the possibility that, by mistake, the upper mines should be set free before the lower 55 mines have been discharged, there is provided a special security device, which acts in the following way:

60 Supposing that it is desired to disengage the upper pivoted brackets, the transmission 29 ought to be put into action, but that is not possible, since the plane screwed to the female screw 30 fixed to the transmission cannot be lowered because it is obstructed by the plane 32. Nor can the transmission 28 of the central pivoted brackets 65 be worked, for plane 32, like plane 31, lies over plane 33.

It is obvious, therefore, that the above device is compelled to carry out the operation of discharging the mines in the following order, namely, first the outlet door is opened, then the lower mine of the bed aligned with the door is released, then the central mine, and finally the upper mine in the mine-bed (vertical row) are successively released.

75 In its turn, plane 34 which acts like the pre-

ceding ones, prevents the lowering of plane 33 and consequently of planes 32 and 31 and thus prevents the operation of discharging the mines, unless it first carries out the operation of opening the discharge door 17 which is done by the transmission 35 which works plane 34.

A mine bed having been discharged, the lowerable planes 24 must be returned to their original position, that is to say, the sliding plane must be formed again with the rings 21 and 22, after 10 which the operation of rotating the cage can be carried out to bring the second mine bed into line with the door 17 and thus discharge the mines contained in it.

To avoid that, by mistake, the rotation of the cage should be effected before the said lowerable planes have been returned to the above position, the safety device 36 is provided, which is connected to plane 33 and makes it possible to put the motor to work and effect the rotation of the 15 cage only when the said plane 33 attached to the respective lowerable planes 24 has, contemporaneously with them, been returned to the original position.

Each mine, at the moment of issuing from the 25 discharge door 17, touches a spring pawl 37 which transmits the movement to the dropping index 38; in addition to indicating that the mine has issued 30 completely, this index also registers the number of mines discharged.

A mechanical index 39 inserted in the crank working the rotation of the cage gives the exact 35 position of the mine bed in relation to the discharge door, on this crank is connected a fine-grooved device for the automatically arresting of the motor which rotates the cage, when the mine bed is perfectly in line with the discharge door.

The discharge of mines may be effected either 40 with the mine chamber completely flooded, or partially flooded or completely dry.

To discharge the mines with the chamber completely flooded, it is necessary:

First, to open the discharge door 17 and the air escape valve 18, both of which are worked from the inside of the ship, thus obtaining the flooding 45 of the mine chamber;

Second, to make sure, by means of the index 39, that the mine bed of the mines to be discharged is in line with the discharge door 17;

Third, to set at work, by means of the relative 50 handle, the transmission 27, which, setting free the lower pivoted brackets 23, leaves the first mine free, which is pushed out of the ship by its own weight;

Fourth, to repeat the operation with transmission 55 28, causing the second mine to fall;

Fifth, to repeat the operation with transmission 29, causing the third mine to fall.

When this last operation is completed, the 60 planes, 31, 32 and 33 must be brought back to their original position, after which the cage can be set in rotation again, carrying the second mine bed into line with the discharge door 17, when the operation of dropping mines can be repeated.

The above operation is repeated to effect the rotation of the remaining mine beds and the discharge of the mines contained in them.

It is obvious that the difference between the weight of the mine and of the water which enters 70 the chamber at each discharge of a mine will be compensated by causing water to flow into the relative compensation compartment of the ship.

To carry out the discharge of mines with the 75 chamber partially flooded, it is necessary:

To open the discharge door 17, making sure that the air-escape valve 18 is closed.

In this way, supposing that the discharge is made at a depth of twenty metres, the air existing in the mine chamber will be compressed at two atmospheres and its volume will be reduced to half; consequently, a quantity of water equal to the half of the volume of the mine chamber will enter the chamber.

10 At this point the crew which is carrying out the operation may enter the mine chamber in the following way:

By opening the watertight door 11 access is had to the recess 12; then, closing the watertight door 11, one gets into the mine chamber, opening the watertight door 13; the discharging operation can be controlled from platforms 14 and 16, and, by means of the relative telephone, it is possible to communicate with the crew in the interior of the ship, who will carry out the discharging operations, working in the same way as that indicated for the discharge of mines with the chamber completely flooded.

25 If it should be desired to discharge the mines with the chamber completely dry, a sufficient quantity of compressed air must be injected into the chamber, to put it into equilibrium with the external pressure of the water.

30 The several mine-beds 9 of the rotatable cage are preferably located as close together as possible (see Fig. 3) save that a space 10 is left between the two of them which are adjacent the platform 14, so that a person may pass between them to the platform 16.

35 The form of execution illustrated and described is susceptible of all those variations and modifications that do not go outside the scope of the present invention.

Thus also, the system which is the subject of 40 this invention may be carried out on any kind of ship and, according to different requirements, the number of mine chambers, the number of layers of mines and the number of the mines themselves may also be varied.

45 What I claim and desire to secure by Letters Patent is:

1. In mine laying apparatus, a vertically disposed water-tight chamber, a mine entrance door in the top thereof and a mine discharge door in the bottom thereof, a cage mounted in said chamber to rotate on a vertical axis, said cage having a plurality of radially disposed mine-beds each constructed to receive mines at the top when in line with said entrance door and to discharge 50 mines at the bottom when in line with said discharge door and to contain a plurality of mines one above the other, means cooperative with each mine-bed for holding the mines in place in the mine-beds, and means for successively releasing 55 the mines, beginning with the lowest one in that mine-bed which is in line with the discharge door, and means to turn the cage to bring successive unloaded mine beds into line with said entrance door and to bring successive loaded mine cages 60 into line with said discharge door.

2. In mine laying apparatus, a vertically disposed water-tight chamber, a mine entrance door in the top thereof and a mine discharge door in the bottom thereof, a cage mounted in said chamber to rotate on a vertical axis, said cage having a plurality of radially disposed mine-beds each constructed to receive mines at the top when in line with said entrance door and to discharge 65 mines at the bottom when in line with said discharge door and to contain a plurality of mines

one above the other, means cooperative with each mine-bed for holding the mines in place in the mine-beds, and means for successively releasing the mines, beginning with the lowest one in that mine-bed which is in line with the discharge door, means to turn the cage to bring successive unloaded mine cages into line with said entrance door and to bring successive loaded mine beds into line with said discharge door, means to open and close said discharge door, and means 10 to restrain said mine-releasing means against operation until after said discharge door shall have been opened.

3. In mine laying apparatus for vessels having water-tight walls dividing their hulls into water-tight compartments; a water-tight cylinder built into one of said walls in a vertical position with its bottom at the bottom of the vessel, a discharge door through the hull bottom from said cylinder, a mine-entrance door 15 at the top of said cylinder, a mine cage rotatably mounted on a vertical axis in said cylinder and having a set of mine-beds each constructed to receive a plurality of mines in vertical arrangement through said entrance door and to 20 discharge the same through said discharge door, means to open and close said doors, and means to release the mines through the discharge door from one mine-bed at a time, and means to turn 25 said cage.

4. In mine laying apparatus for vessels having water-tight walls dividing their hulls into water-tight compartments; a water-tight cylinder built into one of said walls in a vertical position with its bottom at the bottom of the vessel, a 30 discharge door through the hull bottom from said cylinder, a mine-entrance door at the top of said cylinder, a mine cage rotatably mounted in said cylinder and having a set of mine-beds each constructed to receive a plurality of 35 mines in vertical arrangement through said entrance door and to discharge the same through said discharge door, means to open and close said doors, means to release the mines through the discharge door from one mine-bed at a time, 40 means to turn said cage, a water-tight door in the side of said cylinder, a water-tight recess in the hull with which said side door communicates, another water-tight door to effect communication between a compartment of the vessel and said recess, and a platform carried by 45 said cage upon which a person may stand to inspect the mines in the mine-beds.

5. In a mine-laying apparatus, an upright water-tight cylinder having a door in the top for insertion of mines and a door at the bottom for discharge of mines, a cage rotatably mounted within said cylinder and having a plurality of radially disposed mine-beds each designed to receive a plurality of mines in superposed relation, pivoted elements for holding each mine separately in place, tracks in said cylinder for holding said pivoted elements against mine-releasing action save at a position where the mine-bed is located over the discharge door, manually controlled means at that position for holding and releasing the mines in the mine-bed which is lined up with said discharge door, and means to open and close said discharge door.

6. In a mine-laying apparatus, an upright water-tight cylinder having a door in the top for insertion of mines and a door at the bottom for discharge of mines, a cage rotatably mounted within said cylinder and having a plurality of radially disposed mine-beds each designed to receive a plurality of mines in superposed rela- 70

- tion, pivoted elements for holding each mine separately in place, tracks in said cylinder for holding said pivoted elements against mine-releasing action save at a position where the mine-bed is located over the discharge door, manually controlled means at that position for holding and releasing the mines in the mine-bed which is lined up with said discharge door, means to open and close said discharge door, and means to hold said mine-releasing means from operation until said discharge door is open.
7. In a mine-laying apparatus, an upright water-tight cylinder having a door in the top for insertion of mines and a door at the bottom for discharge of mines, a cage rotatably mounted within said cylinder and having a plurality of radially disposed mine-beds each designed to receive a plurality of mines in superposed relation, pivoted elements for holding each mine separately in place, tracks in said cylinder for holding said pivoted elements against mine-releasing action save at a position where the mine-bed is located over the discharge door, manually controlled means at that position for holding and releasing the mines in the mine-bed which is lined up with said discharge door, means to open and close said discharge door, means to hold said mine-releasing means from operation until said discharge door is open, and means to cause said mine-releasing means to operate only to release the mines in vertical succession commencing first with the lowest mine in the bed.
8. In mine laying apparatus for vessels having water-tight walls dividing their hulls into water-tight compartments; a water-tight cylinder built into one of said walls in a vertical position with its bottom at the bottom of the vessel, a discharge door through the hull bottom from said cylinder, a mine-entrance door at the top of said cylinder, a mine cage rotatably mounted in said cylinder and having a set of mine-beds each constructed to receive a plurality of mines in vertical arrangement through said entrance door and to discharge the same through said discharge door, means to open and close said doors, means to release the mines through the discharge door from one mine-bed at a time, means to turn said cage, a water-tight door in the side of said cylinder, a water-tight recess in the hull with which said side door communicates, another water-tight door to effect communication between a compartment of the vessel and said recess, a platform carried by said cage upon which a person may stand to inspect the mines in the mine-beds, and means actuated by the mine which is being discharged for recording the discharge of the mines through the discharge doorway.
9. In a mine-laying apparatus, an upright water-tight cylinder having a door in the top for insertion of mines and a door at the bottom for discharge of mines, a cage rotatably mounted within said cylinder and having a plurality of radially disposed mine-beds each designed to receive a plurality of mines in superposed relation, pivoted elements for holding each mine separately in place, tracks in said cylinder for holding said pivoted elements against mine-releasing action save at a position where the mine-bed is located over the discharge door, manually controlled means at that position for holding and releasing the mines in the mine-bed which is lined up with said discharge door, means to open and close said discharge door, means to hold said mine-releasing means from operation until said discharge door is open, means to cause said mine-

releasing means to operate only to release the mines in vertical succession commencing first with the lowest mine in the bed, and means actuated by the mine which is being discharged for recording the discharge of the mines through the discharge doorway.

10. In mine laying apparatus, a vertically disposed water-tight chamber, a mine entrance door in the top thereof and a mine discharge door in the bottom thereof, a cage mounted in said chamber to rotate on a vertical axis, said cage having a plurality of radially disposed mine-beds each constructed to receive mines at the top when in line with said entrance door and to discharge mines at the bottom when in line with said discharge door and to contain a plurality of mines one above the other, means cooperative with each mine-bed for holding the mines in place in the mine-beds, means for successively releasing the mines, beginning with the lowest one in that mine-bed which is in line with the discharge door, means to turn the cage to bring successive unloaded mine beds into line with said entrance door and to bring successive loaded mine cages into line with said discharge door, and means to render said cage-turning means inoperative while said discharge door is open and the mines from a mine-bed are being discharged.

11. In mine laying apparatus for vessels having water-tight walls dividing their hulls into water-tight compartments; a water-tight cylinder built into one of said walls in a vertical position with its bottom at the bottom of the vessel, a discharge door through the hull bottom from said cylinder, a mine-entrance door at the top of said cylinder, a mine cage rotatably mounted in said cylinder and having a set of mine-beds each constructed to receive a plurality of mines in vertical arrangement through said entrance door and to discharge the same through said discharge door, means to open and close said doors, means to release the mines through the discharge door from one mine-bed at a time, means to turn said cage, and means to render said cage-turning means inoperative while said discharge door is open and the mines from a mine-bed are being discharged.

12. In mine laying apparatus for vessels having water-tight walls dividing their hulls into water-tight compartments; a water-tight cylinder built into one of said walls in a vertical position with its bottom at the bottom of the vessel, a discharge door through the hull bottom from said cylinder, a mine-entrance door at the top of said cylinder, a mine cage rotatably mounted in said cylinder and having a set of mine-beds each constructed to receive a plurality of mines in vertical arrangement through said entrance door and to discharge the same through said discharge door, means to open and close said doors, means to release the mines through the discharge door from one mine-bed at a time, means to turn said cage, a water-tight door in the side of said cylinder, a water-tight recess in the hull with which said side door communicates, another water-tight door to effect communication between a compartment of the vessel and said recess, a platform carried by said cage upon which a person may stand to inspect the mines in the mine-beds, means actuated by the mine which is being discharged for recording the discharge of the mines through the discharge doorway, and means to render said cage-turning means inoperative while said discharge door is open and the mines from a mine-bed are being discharged.

13. In a mine-laying apparatus, an upright water-tight cylinder having a door in the top for insertion of mines and a door at the bottom for discharge of mines, a cage rotatably mounted within said cylinder and having a plurality of radially disposed mine-beds each designed to receive a plurality of mines in superposed relation, pivoted elements for holding each mine separately in place, tracks in said cylinder for holding 5 said pivoted elements against mine-releasing action save at a position where the mine-bed is located over the discharge door, manually controlled means at that position for holding and releasing the mines in the mine-bed which is

lined up with said discharge door, means to open and close said discharge door, means to hold said mine-releasing means from operation until said discharge door is open, means to cause said mine-releasing means to operate only to release the 5 mines in vertical succession commencing first with the lowest mine in the bed, and means actuated by the mine which is being discharged for recording the discharge of the mines through the discharge doorway, and means to render said cage- 10 turning means inoperative while said discharge door is open and the mines from a mine-bed are being discharged.

AMATO CAPPONI.
